A. T. PHILLIPS.
SHOE HEEL PROTECTOR.
FILED AUG. 16, 1910.

Fig. 2.

Inventor
ANNETTE TOWNSEND PHILLIPS
By her Attorney
Norman T. Clark

UNITED STATES PATENT OFFICE.

ANNETTE TOWNSEND PHILLIPS, OF GOSHEN, NEW YORK.

SHOE-HEEL PROTECTOR.

Application filed August 16, 1919. Serial No. 317,874.

To all whom it may concern:

Be it known that I, ANNIE TOWNSEND PHILLIPS, a citizen of the United States, residing at Goshen, in the county of Orange, State of New York, have invented certain new and useful Improvements in Shoe-Heel Protectors, of which the following is a specification, reference being had to the accompanying drawings, illustrative of one particular embodiment of my invention.

This invention relates to devices intended to protect the heel of a shoe from wear under special circumstances. In particular, in the case of operating an automobile a lady's shoe is so formed that the heel engages the footboard or objects when the foot is on a pedal, and the bowl of the heel, namely, the rear part of the upper, is subjected to abrasion by wear, and even with the best of care in the case of light colored shoes they are soiled, if not ruined by such use. Rather than the inconvenience of changing shoes, the protection of the heel by a supplementary device affords a much needed saving, and the protecting device may be made of material and in form so durable as to out wear any number of shoes. The use of such an article requires, however, the production of something reasonable in cost, durable and particularly readily attachable and removable. While devices for this purpose have been suggested, my invention comprises an improvement meeting all the special conditions involved essential to the production of a commercially practical article.

In the accompanying drawings I have shown one form in which:

Fig. 1 illustrates the device attached to a shoe with the foot in normal position. Fig. 2 is a side view of a foot with the device attached in the position of use when guiding the pedal of a motor car.

In the drawings, A is the shoe proper, B is the protector with reinforced portion C in the position where it is subjected to the greatest wear. The entire protector is made to fit the bowl of the heel snugly, while the reinforcing may be a thin sole leather or a thick padded portion of any material desired,—the whole being held firmly in position by the instep strap D.

The strap portion is preferably made with an adjusting buckle d' to adjust it to a proper size to fit the particular user, and the ordinary snap catches with complementary

parts on the protector and the end of the strap D are located as shown at d, so that they may be readily removed. To prevent the protector from slipping upwards, I prefer to add a transverse strap E passing under the small of the foot in front of the heel, but leaving an opening between the strap and the lower corner b of the protector amply large to permit the passage of the heel a.

The upper edge b of the protector is preferably strengthened or stitched, and likewise the other edges, where necessary to transmit the holding strain of the instep strap, but in particular the upper edge b' I prefer to be so arranged and made that it will be below the edge a' of the shoe upper proper, so as to avoid any contact and abrasion with the stocking or heel of the user.

It will be seen that the protector may be equally well applied to a shoe, oxford or pump. In particular, the bowl of the heel being the rear portion of the upper as it merges into the heel proper, affords a convex surface to which my protector may be so fitted as to insure security against its displacement or movement, when tightly held by the ankle strap. In some cases, however, the configuration of the shoe is such that a protector can be made with a suitable spring or other construction embodied so that it can be securely clamped by pressing on from the rear, and held tight against ordinary operation without the necessity of the strap.

The buckle at d' may be in any form desired and may embody the quick-release feature instead of having the snaps d—d at the end of the strap, likewise a tongue or other protection strip may be placed under the buckle for comfort, or definite sizes of strap may be used without the necessary adjustment, or a series of snaps may form the readily detachable connection in a manner to give different lengths, thereby eliminating the buckle and simplify the construction.

The entire article may be made of kid, or any other desired leather or fabric, while the reinforcing material, preferably sole leather, may be varied as to material and thickness, and the outer surface of the reinforcement may be flattened transversely to prevent the rocking of the foot.

In various ways my invention may be

modified for simplicity, cheapness of construction, durability and ready application and removal.

It will be noted that in detaching the device the snaps are released and the entire protector removed without the necessity of handling any of the lower edge, or such portion as may have become soiled, which insures its use with the added advantage of avoiding any soiling of the hands or gloves. This and the protection to the shoe have become of importance in view of the great increase of operation of cars by ladies and their desire to operate cars without any special preparation and frequently when shod with expensive shoes most liable to damage.

While variations in design and material may be made from the particular embodiment herein shown and described, what I claim and desire to secure by Letters Patent is:

1. A protecting device for a shoe having a projecting counter overhanging a relatively small heel, comprising a body portion surrounding the counter of the shoe at its main protuberant area and extending part way down the rear side of the heel, two forwardly extending sides adapted to lie against the sides of the shoe and a uniting member at their forward lower extremity forming a relatively large opening through which the

heel will freely pass said member having its broad surface parallel with the sole, and a detachable instep strap adapted to hold the side portions of the protector against displacement by upper strain on the member uniting the sides underneath the arch. 35

2. A protector for a shoe having an overhanging counter and forwardly inclined heel, 40 comprising a body portion having a wearing surface extending over the protuberance of the counter and part way over the heel, sides extending forwardly with the lower margin extending upwardly to the junction 45 of the arch and the heel and united by an integral member attached to the sides at the edge of the arch said member having its broad side parallel with the sole of the shoe, forward sections of the sides extending 50 upwardly from the arch member and having readily detachable devices adapted to permit vertical strain from the arch member to an instep strap and means for adjustment and release of said instep strap. 55

In testimony whereof, I have signed my name to this specification, in the presence of two subscribing witnesses, this 8th day of August, 1919.

ANNETTE TOWNSEND PHILLIPS.
